(57) **CLAIM**

The ornamental design for a hutch unit, as shown and described.

DESCRIPTION

FIG. 1 is a front, right side perspective view of my design; the door panels are made from a semi-transparent material; FIG. 2 is a front view of the hutch unit of FIG. 1; FIG. 3 is a left side view of the hutch unit of FIG. 1; FIG. 4 is a right side view of the hutch unit of FIG. 1; and, FIG. 5 is a top plan view of the hutch unit of FIG. 1. The features shown in broken lines are not part of the claimed design.
